UNITED STATES PATENT OFFICE.

GEORGE E. STEPHENS, OF KNOXVILLE, IOWA.

WHIFFLETREE-HOOK.

1,102,450.

Specification of Letters Patent. Patented July 7, 1914.

Application filed April 18, 1914. Serial No. 832,872.

To all whom it may concern:

Be it known that I, GEORGE E. STEPHENS, a citizen of the United States, residing at Knoxville, in the county of Marion and State of Iowa, have invented certain new and useful Improvements in Whiffletree-Hooks, of which the following is a specification, reference being had to the accompanying drawings.

This invention relates to new and useful improvements in hooks, and more particularly to whiffletree hooks which are employed to connect the end of a harness trace to the end of a whiffletree.

An object of this invention is the provision of a whiffletree hook which comprises a threaded stem for engagement in the end of a whiffletree, the stem having an end plate formed thereon which extends at right angles to the longitudinal plane of the stem, the forwardly extending end of the plate being enlarged to prevent accidental disengagement of the trace from the hook.

A further object of this invention is the provision of a whiffletree hook, in which the forwardly projecting portion of the end plate is of relatively greater width than the rearwardly extending portion thereof, the width of the forwardly extending portion of the plate being slightly of less length than the eye in the trace so that the trace may be engaged over the forward end of the plate by disposing the rear end of the trace to a position at right angles with relation to the longitudinal plane thereof.

With these and other objects in view, my invention consists in the novel construction to be hereinafter more fully described, claimed, and illustrated in the accompanying drawing, in which,

Figure 1 is an elevational view looking at the end of my improved device; and Fig. 2 is a top view thereof, showing the whiffletree in section.

Referring more particularly to the drawing, the numeral 1 designates one end of the whiffletree upon the extremity of which is mounted a ferrule 2 of the usual construction to prevent splitting of the end of the whiffletree. My improved hook comprises a stem 3 which is threaded at its inner end as at 4, the inner end of the stem being adapted for engagement in the end of the whiffletree 1. The opposite end of the stem projects outwardly from the whiffletree, and is provided at its extremity with

an end plate 5 which extends in a horizontal plane at right angles to the longitudinal plane of the stem. The forward end of the plate which is relatively longer than the rear end thereof, is enlarged to form a head 6, the forward edge of the head being curved as at 7, that portion of the plate between the head 6 and the stem being reduced as at 8. The rear end 9 of the end plate 5 is tapered from the stem 3 to a point at the rear extremity of the plate, the upper and lower edges of the rear end of the plate being beveled as at 10 from the outer face to the inner face thereof. Any trace or cock eye of ordinary construction may be used in connection with my hook the trace 11 in the accompanying drawing being provided with the usual eye 12 adjacent the rear end thereof.

In the practical use of my device, the hook is connected to the whiffletree so that the plate 5 extends forwardly thereof, and when it is desired to connect the trace to the hook, the rear end of the trace is disposed in a vertical position so that the eye 12 therein may be passed over the head 6 of the plate, whereupon the rear end of the trace is drawn upwardly to engage the inner wall of the eye 12 against the lower wall of the reduced portion 8 of the plate, so that the extremity of the trace above the plate may be swung rearwardly and downwardly, the reduced portion 8 of the plate forming a fulcrum so that the eye may pass over the relatively short rear end of the plate, whereupon the rear end of the trace may be moved inwardly upon the stem 3. It will be seen that when the trace is in use, the same will be drawn forwardly so that the rear wall of the eye 12 therein engages the stem 3, and as the head 6 of the plate is relatively of much greater width than the width of the eye 12 in the trace, accidental disengagement of the trace from the hook is prevented. When it is desired to remove the trace from the hook, the trace is moved rearwardly until the forward end of the eye therein engages the stem 3, whereupon that portion of the trace rearwardly of the stem is swung outwardly so that the eye passes over the reduced rear end of the plate 5, whereupon the rear end of the trace may be again disposed vertically around the reduced portion 8 of the plate so that the eye 12 in the trace extends in the same plane as the head 6 of the plate, and in this posi-

tion, the trace may be readily passed over the head and removed from the hook.

From the above description, taken in connection with the accompanying drawing, it will be seen that I have provided a whiffle-tree hook which may be formed of one piece of material so that the same may be cheaply manufactured, the hook being of such construction that accidental disengagement of a trace therefrom is prevented, as it is necessary to dispose the rear end of the trace in a vertical position at right angles to the plane of the end plate of the hook before the same may be removed from the hook.

Having thus fully described my invention, what I desire to secure and claim by Letters Patent, is:—

A whiffle-tree hook comprising a stem

adapted for engagement in the end of a whiffle-tree, an end plate connected intermediate of its ends to the outer end of said stem, said end plate being disposed in a plane at right angles to the longitudinal plane of the stem, the forward end of said plate being enlarged to form a head, the portion of the plate between said head and the stem being reduced, and the rear end of said plate being tapered from the stem to the rear extremity of said plate.

In testimony whereof I hereunto affix my signature in the presence of two witnesses.

GEORGE E. STEPHENS.

Witnesses:

HARRY J. CORE,
J. D. SCHLOTTERBACK.
